UNITED STATES PATENT OFFICE.

BENJAMIN WOLHAUPTER, OF NEW YORK, N. Y., ASSIGNOR TO THE RAIL JOINT COMPANY,
OF NEW YORK, N. Y., A CORPORATION OF NEW YORK.

INSULATED RAIL-JOINT.

No. 889,288.

Specification of Letters Patent.

Patented June 2, 1908.

Application filed January 19, 1907. Serial No. 353,013.

To all whom it may concern:

Be it known that I, BENJAMIN WOLHAUPTER, a citizen of the United States, residing at New York city, in the county of New York, 5 and State of New York, have invented certain new and useful Improvements in Insulated Rail-Joints, of which the following is a specification.

This invention relates to that class of rail joints embodying in their organization a sectional or two-part supporting base for the rail ends whereby each base section affords one rail end a support on both sides of the meeting point of the rail ends without contact with the corresponding base plate section.

To this end the invention contemplates an improved rail joint structure having the same general objects in view as those carried out 20 in connection with the forms of insulated rail joints disclosed and claimed in companion applications filed November 8, 1906, and bearing Serial Numbers 342, 523, and 342, 524. At the same time the invention 25 primarily has in view a novel and effective reorganization in the construction of those types of angle bars characterized as reinforced angle bars, whereby all of the desirable reinforcing features of bars of this type 30 may be preserved in connection with the added functions of a two-part or sectional base plate construction wherein a separate base plate section is arranged to receive and support one rail end in such a manner that 35 each of said sections affords one rail end a support on both sides of the meeting point of the rails without metallic or electrical contact with the corresponding base section.

A further general object of the invention is 40 to so arrange the separate base plate sections in connection with the angle bars of the joint as to provide for a maximum reinforcing and strengthening of the entire joint structure, while at the same time permitting 45 of a thorough and effective insulation of the joint with the use of a minimum amount of insulating material.

A further object of the invention is to 50 provide a novel and effective arrangement of the separate base plate sections, or separate base supports, so as to accomplish the objects above indicated, and yet provide no base support resting on the ties. In this particular the present invention distinguishes

from the companion applications referred 55 to, for inasmuch as while there is a direct bearing of the rail on the metal of the reinforced bar, still the load applied thereon is not delivered to the ties directly, but through 60 the insulation.

With these and many other objects in view, which will more readily appear to those familiar with the art, the same consists in the novel construction, combination and arrangement of parts hereinafter more fully 65 described, illustrated, and claimed.

The essential features of the invention involved in the application of the two-part or sectional base plate construction to reinforced types of angle bars, are necessarily susceptible to a wide range of modification without departing from the scope of the invention, but certain preferred practical embodiments thereof are shown in the accompanying drawings, in which:

Figure 1 is a side elevation of a rail joint having angle bars of the reinforced type, and also embodying the present invention. Fig. 2 is a cross sectional view of the rail joint shown in Fig. 1 on the line of section 2—2 of 80 said figure. Fig. 3 is a horizontal sectional view on the line 3—3 of Fig. 2 showing the relation of the separate base plates to the rail ends. Fig. 4 is a detail perspective view of one of the angle bars of the joint shown in Fig. 1 illustrating such angle bar and its base plate section in separated or detached relation. Fig. 5 is a view similar to Fig. 4 of the opposite angle bar of the joint and its base plate section in separated relation. Fig. 6 85 is a view similar to Fig. 1 of another form of rail joint, of the reinforced angle bar type, illustrating the application of the invention thereto. Fig. 7 is a cross sectional view on the line 7—7 of Fig. 6. Fig. 8 is a horizontal 90 sectional view on the line 8—8 of Fig. 7 showing in plan the relation of the base plate sections or elements of the form of joint shown in Figs. 6 and 7. Fig. 9 is a side elevation similar to Figs. 1 and 6, illustrating another 100 form of rail joint, of the reinforced angle bar type, embodying the present invention. Fig. 10 is an enlarged sectional view on the line 10—10 of Fig. 9. Fig. 11 is a horizontal 105 sectional view on the line 11—11 of Fig. 10 showing in plan, the base plate arrangement of the rail joint shown in Figs. 9 and 10. Fig. 12 is a side elevation of another form of rail

joint, of a reinforced angle bar type, embodying the present invention. Fig. 13 is a cross sectional view on the line 13—13 of Fig. 12. Fig. 14 is a horizontal sectional view on the line 14—14 of Fig. 13 showing in plan the base plate arrangement of the rail joint illustrated in Figs. 12 and 13.

Like reference numerals designate corresponding parts in the several figures of the drawings.

As above indicated, the distinctive feature of the present invention resides in associating with splice bars or fish plates, of the reinforced angle bar type, a rail supporting base or base plate made in two sections or parts whereby each supporting base or base plate section receives thereon one rail end only, while at the same time each of said sections of the supporting base affords the rail end thereon a support on both sides of the meeting point of the rail ends, and hence the support of the ties on both sides of said meeting point, without metallic or electrical contact with the corresponding section of the supporting base. Also, in adapting the two-part or sectional rail supporting base to angle bars of the reinforced type, the present invention presents the distinctive feature of an insulated rail joint wherein there is no base support resting on the ties, and though there is a direct bearing of each rail end on the metal of the reinforced bar, still the load applied thereon is not delivered to the ties directly, but through insulation. These features of construction may be utilized in a variety of ways and combined with divers forms of rail joints having reinforced angle bars without affecting the scope or general purposes of the invention, but for illustrative purposes a few preferred forms of joints are shown in the drawings to exemplify the special features claimed, and particular reference will now be made to these forms.

Referring to the type of joint illustrated in Figs. 1 to 5 inclusive of the drawings, it will be observed that this joint includes in its construction the adjacent service or running rails 1 and 2, the oppositely arranged side angle bars 3 and 4, and the joint bolts 5 passing through the usual bolt holes in the angle bars and in the webs of the rail ends. The present invention contemplates no special change in the mounting or insulating of the bolts, so for illustrative purposes there are shown, in the figures of the drawings referred to, the conventional joint bolts having the usual heads and nuts 6 and 7, at the inner sides of which are arranged the insulating washers 8 and the metal backing washers 9 interposed between the insulating washers and the heads and nuts of the bolts. In this form of construction it is also preferable to associate with the joint bolts, insulating bushings 10 adjoining the inner faces of the insulating washers 8 and lining the bolt holes

in the angle or splice bars. However, these details may be utilized or omitted without affecting the invention.

The opposite angle bars 3 and 4 are preferably of duplicate design and construction and each of the same is of the type commonly characterized as a reinforced angle bar wherein definite provision is made for strengthening, trussing and reinforcing the angle bar in the vertical plane of the joint between the meeting ends of the service or running rails. In the form of rail joint shown in Figs. 1 to 5 inclusive of the drawings, each of the reinforced angle bars 3 and 4 is provided with the usual main splice bar portion 11, and with the head and foot flanges 12 and 13, respectively coöperating with the head and base of the rail. In addition to these elements, each of the angle bars is provided at a point intermediate its ends with a centrally arranged pendent reinforcing leg 14 preferably formed integrally with the foot flange of the bar and projected downwardly from the outer edge of the said foot flange. The reinforcing leg 14 is arranged beyond the edge of the rail base or base flange and extends a distance below the bottom of the rail base to effect a stiffening and reinforcing of the intermediate portion of the angle bar extending over the joint between the meeting ends of the rails. These are the functions of a reinforcing leg projected downwardly from the foot flange of an angle bar intermediate the ends of the latter, and in the particular form of joint described, the reinforcing leg 14 of each angle bar not only projects below the plane of the bottom of the rails or rail bases, but also is deflected inwardly at an angle beneath the rail bases, as plainly shown in Fig. 2 of the drawings. In adapting the sectional or two-part rail supporting base to this construction, the separate base plate sections 15 and 16 are respectively supported on and carried by the reinforcing legs 14 of the opposite angle bars. In one form of construction that may be advantageously employed, each base plate section 15 and 16 is formed with a main horizontal flat body portion which provides a supporting seat or rest for one rail end, and at one end the said body portion of each base plate section has bent therefrom an angularly or obliquely disposed supporting flange 17 which conforms to the inclination of the reinforcing leg 14 with which it is associated. In the construction shown in Fig. 2 of the drawings the angularly or obliquely disposed supporting flange 17 of each base plate section projects below the plane of the top portion of the plate from which it is bent and is deflected inwardly toward the longitudinal center line of the rails, so that in the assembling of the several elements, each base plate section 15 and 16 has its pendent inwardly deflected and oblique supporting flange 17 arranged flat upon the inner side

of the reinforcing leg 14 of one angle bar and secured rigidly to such leg by means of rivets, bolts, or equivalent fastening devices 18. This construction makes each base plate 5 section a rigid part of each angle bar so that such base plate section receives the benefit of the supporting effect of the angle bar and its reinforcing leg with the result of providing a firm and substantial base support for 10 one rail end.

It will be observed that in the form of the invention being described, the base plate sections are arranged in alternated relation, that is, one base plate section is supported on 15 and fastened to one end portion of the reinforcing leg 14 of one angle bar, while the other base plate section is supported on and fastened to the diagonally opposite end portion of the reinforcing leg 14 of the opposite 20 angle bar. Hence, the two base plate sections 15 and 16 are arranged in spaced parallel relation in different transverse planes and are respectively supported from diagonally opposite portions of the separate angle 25 bars, so that each section of the rail supporting base or base plate affords one rail end the indirect support of the ties T on both sides of the meeting point of the rails without mechanical or electrical contact with the corresponding base section. 30

In carrying out the invention, each base plate section 15 and 16 may be made of any suitable length so as to extend entirely or only partly across the bottom of the rail 35 bases, but in all constructions and forms each base plate section is arranged to receive thereon one rail end only. Also, in carrying out the invention the reinforcing leg 14 of each angle bar may be of any desired or preferred length, but in the type of rail joint 40 construction shown in Figs. 1 to 5 of the drawings, the said reinforcing leg 14 of each angle bar is illustrated as being of a length equaling and slightly exceeding the combined widths of the two base plate sections 45 15 and 16, thereby contributing materially to the effective stiffening and reinforcing of each angle bar at both sides of the meeting point of the rail ends.

50 It is to be further noted in the construction described, that the pendent reinforcing legs 14 of the opposite angle bars are located wholly in a plane between the opposite ties T above which the end portions of the angle 55 bars lie, so that the separate oppositely related base plate sections have no direct support on the ties, while at the same time there is a direct bearing of each rail on a metal base plate section, and the load applied to 60 the joint is not delivered to the ties directly but through insulation.

The insulating of a joint constructed as described can be effected very thoroughly by the simple insulating expedients of utilizing 65 side insulating sheets 19 between the sides of

the rails and the rail adjoining faces of the angle bars, and having an insulating end post 20 between the rail ends which is arranged to have its base 21 project below the plane of the rail bases so as to lie interposed 70 between the inner spaced adjacent edges of the separate base plate sections 15 and 16.

Another form of rail joint of the reinforced angle bar type, which may be reorganized to embody the present invention is shown in 75 Figs. 6, 7 and 8 of the drawings. In this construction, each angle bar 22 and 23 is provided with the usual head and foot flanges 24 and 25 respectively, and the foot flange 25 thereof is formed intermediate its ends with 80 an integral rail clasp 26 adapted to clasp over the edge of the base flange of the rail. The rail clasp 26 of each angle bar 22 and 23 in effect, constitutes a bottom reinforcing extension which is formed below the plane of 85 the rail base with an inwardly extending horizontal rail supporting or base plate section 27 presenting a flat supporting shoulder or face upon which the rail base rests. In this construction the inwardly extending 90 base plate section 27 of each angle bar has bent from its inner edge a pendent vertically disposed reinforcing leg 28 which itself is stiffened by forming the same at the inner side of its lower edge with a reinforce rib 95 29. The distinctive feature of the form of 100 joint shown in Figs. 6, 7, and 8, resides in preserving the same two-part or sectional base plate arrangement as embodied in the form of joint shown in Figs. 1 to 5 inclusive 105 of the drawings. To provide for this the reinforcing legs 28 and the base plate sections 27 of the opposite angle bars are arranged in staggered, or diagonally opposite relation whereby the base plate section 27 of one angle bar is arranged to extend beneath and 110 support one rail end, while the base plate section of the opposite angle bar is arranged to extend beneath and support the other rail end. In this arrangement the same mechanical functions are preserved as in the 115 form of joint already described, while the insulation of the joint may be effected in the same way, viz: through the employment of the side insulating sheets 19 and the insulating end post 20 previously described. Also, the joint bolts and joint bolt insulation may remain the same as described, and hence, similar reference characters will apply to similar parts in Figs. 1 to 8 inclusive. 120

Another variation of the invention is suggested in Figs. 9 to 11 inclusive of the drawings wherein the sectional or two-part base construction is shown applied to a rail joint having reinforced angle bars provided with 125 pendent reinforcing legs disposed vertically. Referring particularly to this modification, the reference characters 30 and 31 designate the opposite angle bars, each of which is provided at the outer edge of its foot flange 32 130

with a pendent vertically disposed reinforcing leg 34, and to the inner side of the leg 34 of each angle bar is riveted, bolted, or otherwise suitably fastened, as at 35, the angularly disposed supporting flange 36 bent downwardly from the outer edge of a base plate section. The separate base plate sections are designated respectively by the numbers 37 and 38 and preserve the same relative arrangement as the base plate sections shown in the other views of the drawings. However, in this form of the invention, as well as in the form shown in Fig. 7 of the drawings, the individual base plate sections 15 are illustrated as extending only partly across the bottom of the rail bases, while at the same time preserving the spaced parallel relation of the separate base plate sections so that each base section receives and supports 20 thereon one rail end. Also, in the form of the invention shown in Figs. 9, 10, and 11 of the drawings, there is suggested the idea of having each reinforcing leg 35 of a length substantially equaling the width of the base 25 plate section supported thereby, so that not only the base plate sections, but also the reinforcing legs of the opposite angle bars preserve a diagonally opposite relation. To provide for insulating the joint shown in 30 Figs. 9 to 11 inclusive, the same insulating expedients already described may be utilized, viz: side insulating sheets 19 and the insulating end post 20 interposed between the rail ends.

35 A further adaptation of the invention is illustrated in Figs. 12, 13, and 14 of the drawings. In these figures of the drawings a joint is shown involving the opposite side angle bars 39 and 40 each of which is provided with a foot flange 41 having formed integral with its lower edge, intermediate the ends of the bar, the integral horizontal base plate section 42 and at the outer edge of said base plate section with a reinforce flange 43. 40 The base plate section 42 of each of the angle bars 39 and 40 extends horizontally beneath a rail base and is disposed in diagonally opposite relation to the base plate section 42 of the opposite angle bar. This construction 45 preserves the spaced parallel relation of the two base plate sections in different transverse planes so that each of said sections supports directly thereon one rail end only. In this respect the two-part base plate arrangement 50 is the same as involved in all other forms of the invention and specifically is substantially the same as the base plate arrangement shown in the group of Figs. 6 to 11 inclusive of the drawings. It will be observed that the 55 modification shown in Figs. 12 to 14 inclusive involves the feature of locating the base plate of each angle bar at one side of the transverse center of such angle bar, but by reason of the diagonally opposite relation of 60 the separate base plate sections, there is a

mutual intersupporting of such parts, which serves to uniformly distribute the load throughout the joint.

In connection with the modified joint shown in Figs. 12, 13, and 14 there is suggested a modified insulating expedient that may be employed in this and in all other forms, viz: that of using what may be termed a one end insulation for each angle bar, which one end insulation consists of a sheet 44 of insulating material interposed between one end portion of each angle bar and one rail end, the insulating sheets 44 for the opposite angle bars being disposed in diagonally opposite relation. This gives a direct metallic bearing of the joint with the rail throughout half the length of the joint without the interposition of soft relatively compressible material, while at the same time economizing insulating material and effecting a complete insulation of the joint in connection with the joint bolt insulation and in connection with the end post insulation 20 previously described. The modification of the insulation, as shown in Figs. 12, 13, and 14 is necessarily applicable to all of the other forms of the invention herein described. ..

Various other modifications of the invention will readily suggest themselves to those skilled in the art and it will be understood that various changes in the form, proportion, and minor details of construction may be resorted to without departing from the spirit or sacrificing any of the advantages of the invention.

I claim:

1. In an insulated rail joint, the combination with the rails and ties, of the angle bars each carrying a metallic base arranged for the support of one rail end only, and located between the ties, and insulating means.
2. In an insulated rail joint, the combination with the rails and ties, of the angle bars each carrying a base plate section for one rail end only located between the ties, and insulating means.
3. In an insulated rail joint, the combination with the rails and the ties, of the opposite angle bars each carrying a base plate section for one rail end only, the separate base plate sections being arranged in different transverse planes and both located wholly between the ties, and insulating means.
4. In an insulated rail joint, the combination with the rails and ties, of the angle bars carrying separate base plate sections located between the ties, each base plate section affording one rail end only the indirect support of the ties on both sides of the meeting point of the rails without contact with the corresponding base section, and insulating means.
5. In an insulated rail joint, the rails, and side angle bars each provided with a rein-

100

105

110

115

120

125

130

forcing leg and with a base section for the support of one rail end only, and insulating means.

6. In an insulated rail joint, the rails, and the side angle bars each provided with a reinforcing leg and a base plate section for the support of one rail end, the separate base plate sections having diagonally opposite points of support, and insulating means.

10 7. In an insulated rail joint, the rails, the angle bars each having a reinforcing leg and a base plate section for one rail end carried by said leg, and insulating means.

15 8. In an insulated rail joint, the rails, side angle bars each having a reinforcing leg and a base plate section for one rail end, and insulating means including insulation interposed between the separate base plate sections.

20 9. In an insulated rail joint, the rails, and side angle bars each having a reinforcing leg and a base plate section for one rail end supported on and carried by said leg, and insulating means including insulation interposed 25 between the separate base plate sections.

10. In an insulated rail joint, the rails, side angle bars each provided with pendent reinforcing legs, a base plate section having a supporting flange rigidly connected to the 30 reinforcing leg of each bar, the separate base

plate sections being arranged in different transverse planes and each affording a base support for one rail end only, and insulating means.

11. In an insulated rail joint, the rails, 35 side angle bars each provided with pendent reinforcing legs, a base plate section having a supporting flange rigidly connected to the reinforcing leg of each bar, the separate base plate sections being arranged in different 40 transverse planes and each affording a base support for one rail end only, insulation between the angle bars and the rails, and insulation between the separate base plate sections.

12. In an insulated rail joint, the rails, side angle bars each having a base plate section for one rail end only, the separate base plate sections being arranged in spaced relation and located between the ties, insulation 50 between the angle bars and the rails, and an insulating end post arranged to have its base interposed between the separate base plate sections.

In testimony whereof I hereunto affix my 55 signature in the presence of two witnesses.

BENJAMIN WOLHAUPTER.

Witnesses:

KATHERINE McNALLY,
E. A. VAN DEUSEN.
